GROUND PLATE FOR A SHEATHED, ELECTRIC SURFACE UNIT

Frank T. Walton, 656 13th St.,
Oakmont, Pa. 15139

Filed Apr. 5, 1974, Ser. No. 439,223

Term of patent 14 years

Int. Cl. D8—08

U.S. Cl. D8—229

FIG. 1.

FIG. 2.

FIG. 3.

FIG. 4.

FIG. 5.

FIG. 6.

FIG. 1 is a perspective view looking at one side of a ground plate for a sheathed, electric surface unit, showing my new design,

FIG. 2 is a perspective view looking at the plate from the side opposite to that shown in FIG. 1,

FIG. 3 is a top plan view of the plate,

FIG. 4 is a side elevational view of the plate,

FIG. 5 is a perspective view looking at one side of a modified plate, and

FIG. 6 is a perspective view looking at the plate from the side opposite to that shown in FIG. 5.

I claim:

The ornamental design for a ground plate for a sheathed, electric surface unit, substantially as shown.
